CONTROL OF GAS PRODUCTION IN THE
VAPOR PHASE CONVERSION OF LIQUID
HYDROCARBONSWilliam W. Holland, Baltimore, Md., assignor to
The Gyro Process Company, Detroit, Mich., a
corporation of Michigan

Application October 16, 1948, Serial No. 54,946

9 Claims. (Cl. 196—61)

1

This invention relates to the conversion of heavier hydrocarbons into lighter hydrocarbons, and more particularly to the conversion of liquid hydrocarbons of higher boiling point and while held in the vapor phase into hydrocarbons of lower boiling range suitable for the production of improved motor fuels. It is directed specifically to the relatively high temperature conversion of hydrocarbons without the production of an excessive amount of fixed gas which usually accompanies high temperature operations of this character.

When cracking hydrocarbon oils in the liquid phase, or the mixed liquid and vapor phase, the rate and degree of conversion increase with the rise in temperature, accompanied by a corresponding increase in the production of coke and gas. The temperatures employed in liquid phase cracking are usually within the range of 750° to 950° F., depending upon the character of the charging stock and the degree of conversion desired, the latter being the governing factor in the quality of the cracked product with respect to its anti-knock properties. It is customary, however, in such operations to employ only those temperatures which will produce a moderately high octane distillate, without the production of large amounts of coke and gas, and thereby permit long operating periods on the part of the conversion apparatus and with low maintenance costs. The anti-knock properties of the cracked products of such conversion are improved by the addition thereto of tetraethyl lead or by subsequent refining steps such as alkylation or isomerization. By such methods the octane number of the finished product may be increased to meet the requirements of motor fuel for commercial purposes.

When cracking hydrocarbons in the vapor phase, a distillate is obtained which possesses considerably higher anti-knock properties than liquid phase cracked distillate, so that it is not necessary to subject it to similar methods of after treatment in order to attain a given octane rating. This is due primarily to the inherent difference in the chemical composition of the two types of distillate. No entirely satisfactory explanation has yet been advanced to account for this difference, but it is known that vapor phase cracked distillate contains certain hydrocarbons of cyclic and olefinic configurations, not found in the liquid phase cracked product, which contribute materially to high anti-knock performance.

When cracking petroleum hydrocarbons in the vapor phase more fixed gas is formed than when

2

cracking in the liquid phase because of the higher operating temperatures, which may range from 1100° to 1350° F. when the production of motor fuel is the primary consideration. Liquid fractions may be recovered from the gas, however, by methods of absorption, compression, refrigeration, polymerization and the like, which when added to the cracked motor fuel produce an overall yield comparable with that from liquid phase cracking. But instead of employing such methods to increase the yield of liquid products from vapor phase cracking, as liquid phase cracking processes employ methods of after treatment to improve the anti-knock properties of the distillate, it is more practical to control the gas production and thereby obtain a higher yield of liquid fractions, without the necessity of additional steps for that purpose.

I have observed that as the hydrocarbon vapors pass through the conversion coil, the gas production increases with the progressive rise in temperature, while the production of liquid fractions within the motor fuel boiling range remains substantially constant, particularly in the last half or thereabouts of the coil, and that the gas production reaches its maximum point at the exit of the coil, coincident with the maximum temperature. I have noted also that if the rise in temperature is checked in the mid-section of the coil and maintained at a reasonably constant level thereafter, the gas production is markedly reduced, with a corresponding increase in the motor fuel production. It is concluded therefore that the excessive gas production commonly associated with vapor phase cracking is not due to nominally higher temperatures than those customarily employed in liquid phase cracking, considering the very much shorter time element, but to the excessively high temperatures reached at the end of the vapor phase cracking reaction.

It is, therefore, an object of this invention to provide a method and means to control the vapor phase cracking reaction so that the maximum yield of liquid products within the motor fuel boiling range is obtained, and at the same time preserve the high anti-knock properties characteristic of the distillate.

Another object of this invention is to provide a method and means of temperature control in the conversion coil which will modify the progressive intensity of the decomposition reaction and thereby inhibit the production of excessive amounts of fixed gas.

Another object of this invention is to provide a method and means of temperature control

whereby the vapors undergoing conversion will be subjected to substantially constant temperature conditions during the conversion interval.

A further object of this invention is to produce a vapor phase cracked distillate which will be amenable to treatment by conventional refining methods without excessive losses in volume or octane rating.

It is another object of this invention to provide a method and means to modify the intensity of the temperature conditions to which the conversion elements are exposed and thereby reduce equipment maintenance costs.

It is still another object of this invention to improve the economics of the process generally by simplifying the several steps and by limiting the accessory equipment necessary to its complete performance, thereby affording a wider differential between manufacturing costs and the sales price of the finished products.

Other objects of this invention will become apparent in the further disclosures hereinafter set forth.

Time and temperature are the important factors in any cracking operation, particularly at the high temperatures employed in vapor phase cracking, and unless they are controlled within reasonable limits, the reaction end products may vary considerably. Liquid phase cracking does not present a difficult problem with respect to the reaction time because it is gauged in terms of minutes, and "soaking" coil sections or drums are usually provided in order to insure ample time for completion of the reaction. Pressure is also an important factor in liquid phase cracking, but chiefly as a means of reaching the desired temperature without vaporization of the oil under treatment. On the other hand, in vapor phase cracking the time element is so short, a matter of seconds only, that it is difficult to design equipment which under commercial operating conditions can be controlled with sufficient accuracy with respect to the time-temperature relationship to insure reasonably consistent results over extended operating periods. Any condition which may cause the hydrocarbon vapors to be heated too long or too high a temperature, even for a fraction of a second, is reflected immediately in excess gas production. The tendency seems always to have been in this direction in vapor phase cracking, due perhaps to the limited means provided for controlling the time-temperature reaction conditions. If for any reason the rate of flow of the vapors through the conversion coil should vary or if the furnace temperature should rise or fall, the entire conversion operation is thrown out of balance, with consequent varying results in the end products.

It is therefore a further object of this invention to provide means whereby the vapors passing through the conversion coil are maintained at a substantially constant temperature independently of the rate of flow within reasonable limits or of moderate fluctuations in the furnace temperature.

Means for controlling furnace temperatures have reached a degree of refinement and dependability which leave little to be desired from that standpoint, but the temperature of the vapor within the conversion coil has not been brought under as complete control as could be desired.

Theoretically speaking, as the hydrocarbon vapors pass through the conversion coil, the temperature is raised rapidly until it reaches the predetermined decomposition temperature of the

vapors, at which point it is maintained for a predetermined time to complete the conversion reaction. In actual practice, however, this is not done in the present day conversion coil since the temperature of the vapor rises progressively during its passage throughout the length of the coil, leaving the coil at its maximum temperature. Here we are dealing with the maximum temperature reached in the coil, not with a properly predetermined decomposition temperature of the vapor. It is this peak temperature that is mainly responsible for the high gas production in vapor phase cracking processes. Quenching the vapors immediately upon emergence from the cracking coil arrests the reaction so that no further gas is produced, but it does not reduce the quantity of gas already formed in the coil. Quenching is a means of terminating the reaction and in that respect only it affects the gas production.

Soaking coils have been used as a means of maintaining the vapor at a constant temperature for the required time to effect the desired degree of conversion but they have had little or no effect upon the gas production because of the difficulty of controlling the temperature in such a bank of tubes when in the same furnace setting with the conversion coil, whether located either in the radiant or convection sections. Even if located in a separate furnace, a constant temperature could not be maintained throughout the length of such a coil unless each tube were fired independently. Similar results have been obtained with heavily insulated soaking drums.

I have discovered that internal cooling is a more effective means of maintaining a constant temperature in a vapor phase conversion coil than external heating. In the latter the temperature rises progressively from tube to tube throughout the length of the coil, reaching the maximum temperature at the exit end. At no point in the coil is the temperature actually at a constant level requisite to the uniform cracking of the vapor, which condition results in varying degrees of conversion and a high gas production. On the other hand, if the vapor is heated to the predetermined temperature at which conversion is to be effected and is checked and maintained at that temperature for the required length of time to complete the reaction, uniform cracking results, with only a normal gas production. The temperature required under such conditions is appreciably lower than that customarily employed in vapor phase cracking operations, which contributes not only to a lower gas production but also to a less highly unsaturated distillate which is more readily treated with the usual refining agents, such as sulfuric acid.

I have found also that the rapid rise in temperature in the cracking coil may be readily checked at any desired point by injecting into the vapor stream a cooling agent such as a gaseous or light liquid hydrocarbon (which may also enter into the cracking reaction), low pressure steam, water or any other suitable cooling agent. Water is well adapted to the purpose because of its high latent heat of vaporization, the small amount required to check the rise in temperature and the ease with which it may be introduced at any point or points in the conversion coil. For example, when the vapor has reached the desired temperature at any intermediate point in the coil, the temperature will continue to rise unless it is checked. At this point a fine jet of water is admitted to the coil, sufficient in

amount only to arrest the temperature. Passing through subsequent sections of the coil, the temperature of the vapor again rises, at which point a second jet of water is introduced into the coil, and so on. With the third injection of water sufficient time has elapsed, as a rule for the reaction to have been completed when the vapors leave the coil. It is thus possible to crack hydrocarbons in the vapor phase at a comparatively constant temperature, or within a given temperature range varying only a few degrees, whereas the temperature range during the cracking interval heretofore has been of the order of 100° to 150° F. variation.

The introduction of water, steam or a hydrocarbon cooling agent into the conversion coil through a manifold system under thermostatic control presents no complications in construction or operating difficulties. It is injected into the coil automatically only at the points where and when needed in order to maintain a substantially constant temperature therein. Not only does this means of controlling the temperature reduce the gas production and modify the unsaturated character of the distillate, particularly with respect to diolefins, but less coke is formed under the milder operating conditions.

For a further understanding of the invention, reference is made to the accompanying drawings forming a part of this specification, wherein:

Fig. 1 represents diagrammatically a side elevational view, partly in vertical section, of a vapor phase cracking system employing internal cooling as a means of controlling the conversion coil temperature; and

Fig. 2 is a top plan view partly in horizontal section of the conversion coil and a header or manifold through which a cooling agent is delivered to the coil, together with temperature control devices.

Referring more particularly to the drawing, the numeral 1 represents a pipe line through which a hydrocarbon charging stock is delivered by pump 2 to a vapor phase conversion system wherein the hydrocarbon is decomposed for the primary purpose of producing a superior quality motor fuel, characterized by its high anti-knock properties, without the production of an excessive amount of fixed gas which usually accompanies high temperature operations of this character. The hydrocarbon charge is first heated to its vaporization temperature in a continuous coil 3 suitably located in a furnace setting 4, preferably in the convection section, and is discharged through line 3' into an evaporator 5 wherein the vapors are separated from any unvaporized heavy components of the charge, the latter being withdrawn from the bottom of the evaporator through the valved line 6 and diverted from the system. The vapors leaving the top of the evaporator through line 7 then pass through a bank of drying and preheating tubes 8, also preferably located in the convection section of the furnace, wherein any liquid entrainment carried along mechanically by the vapors is converted into vapor, so that only dried, preheated vapors enter the conversion coil 9.

The temperature of the vaporous hydrocarbons at this stage of the operation reaches the point at which incipient cracking begins, and, according to current practice, it rises rapidly and progressively thereafter during the passage of the vapors throughout the length of the conversion coil. The rate of heat in-put is so rapid during the cracking interval that portions of the vapor,

particularly those adjacent to the inner walls of the tubes, become superheated and are decomposed far beyond the motor fuel stage, with a resultant excessive gas production. This condition is also largely responsible for the presence of certain highly unsaturated compounds in the cracked distillate which render its treatment by conventional methods and agents practically impossible.

To rectify this condition and to modify the decomposition reaction so that it will proceed smoothly and uniformly, means are provided to check the progressive rise in temperature by injecting a cooling agent into the vapor stream at one or more points in the course of its passage through the conversion coil so that it is maintained at a substantially constant temperature during the cracking interval.

Means suitably adapted to this purpose are shown in Fig. 2, wherein the conversion coil 9 is tapped, preferably through the return bend fittings or junction boxes, to receive the pipes a, b and c which are connected with a header 10, to which the cooling agent is supplied by pump 11 through line 12. Valves 13, 14 and 15 provide regulatory means for admitting the cooling agent into the rapidly moving vapor stream in amounts only sufficient to check the rise in temperature. By properly adjusting these valves, the temperature may definitely be controlled within narrow limits, thereby establishing substantially constant temperature conditions throughout the conversion coil.

Such temperature regulation may be accomplished by manual adjustment of the valves or by well known automatic temperature control devices such as those indicated at 16, 17 and 18. The temperature controllers are connected with suitable temperature-sensitive elements inserted into the respective sections of the conversion coil, and with the valves 13, 14 and 15 in such a manner as to adjust the flow of the cooling agent passing through the valves in response to the variations in temperature of the vapors passing through the coil. A surprisingly small amount of the cooling agent is required to maintain a reasonably constant temperature throughout the conversion coil because of the high velocity of the vapor, the short time element between the cooling periods and the effectiveness of the cooling agent, especially when water is used for that purpose.

The cooling operation appears to have no effect whatsoever upon the anti-knock properties of the cracked distillate, although there is a very substantial increase in the liquid volume, with a corresponding decrease in the gas production. The distillate is of a less highly unsaturated character and responds more readily to conventional methods of treatment for the removal of undesirable constituents. A noteworthy feature of the process is the small amount of finely divided coke produced under such temperature controlled conditions.

Leaving the conversion coil through line 9', the products of the decomposition reaction enter a second cooling stage in a temperature arrester 19 where they are brought into intimate and direct contact with a cooling agent produced within the system, reducing the temperature to about 625° F. The mixture of gaseous and liquid products, together with some finely divided coke, then pass through line 19' and into a separator 20 where the light fractions are removed overhead, preferably with the aid of steam, the tarry ma-

terials and suspended coke being withdrawn from the bottom through the valved line 21 and diverted from the system.

The overhead products leaving the separator through line 22 pass into a fractionating column 23, preferably of the bubble tower type, where separation is effected between the light and heavy fractions, the latter being withdrawn from the bottom of the column through line 24, controlled by valve 25, and sent to fuel oil storage or used for other purposes. It may also be returned to the feed stock for reprocessing, if desired. A liquid fraction is withdrawn from an intermediate plate in the bubble tower through line 26 and cooler 27 and collected in the working tank 28 from which a portion is delivered by pump 29 through line 30, controlled by valve 30, to the arrester 19, as a quenching medium to terminate the decomposition reaction of the vapors leaving the conversion coil. Another portion of this liquid may be returned to an intermediate point in the fractionating tower by pump 31 through line 32, as a control medium for the mid-tower temperature if desired.

The overhead from the fractionating tower passes through line 33 and cooler 34 into a gas-liquid separator 35, a portion of the condensate being returned to the top plate of the tower through line 37 for temperature control. The remainder of the condensate is withdrawn from the bottom of the separator through line 38, controlled by valve 39, and sent to the motor fuel treating and finishing system, while the gas leaving the top of the separator through line 40, controlled by valve 41, goes to the gas separating system.

I claim:

1. A process for the conversion of higher-boiling hydrocarbons into lower boiling hydrocarbons, the steps which comprise: heating at non-converting temperatures mixed high and low boiling hydrocarbons to vaporizing temperatures, thereafter separating the vaporized from the unvaporized hydrocarbons, passing the vaporized hydrocarbons through an elongated externally heated conversion zone of restricted cross section, discharging the unvaporized hydrocarbons without returning the same directly to said conversion zone; heating the vaporized hydrocarbons upon their introduction into said zone and their passage therethrough to a desired conversion temperature, and maintaining such conversion temperature of said vaporized hydrocarbons substantially constant during the remaining passage thereof through said conversion zone by introducing into said hydrocarbons, after the latter have attained said conversion temperature, regulated quantities of a fluid coolant selected from the group consisting of gaseous hydrocarbons, light liquid hydrocarbons, steam, and water.

2. A method for converting hydrocarbons in the vapor phase as defined in claim 1, and wherein in the fluid coolant employed in regulating the temperature of the vaporous hydrocarbons undergoing conversion consists of water.

3. A method for converting hydrocarbons in the vapor phase as defined in claim 1, and wherein in the fluid coolant employed in regulating the temperature of the vaporous hydrocarbons undergoing conversion consists of steam.

4. A method for converting hydrocarbons in the vapor phase as defined in claim 1, and wherein in the fluid coolant employed in regulating the temperature of the vaporous hydrocarbons un-

dergoing conversion consists of a low boiling liquid hydrocarbon.

5. A method for converting hydrocarbons in the vapor phase as defined in claim 1, and wherein in the fluid coolant employed in regulating the temperature of the vaporous hydrocarbons undergoing conversion consists of a normally gaseous hydrocarbon.

10 6. A process for the conversion of higher boiling hydrocarbons into lower boiling hydrocarbons, the steps which comprise: passing a stream of such higher boiling hydrocarbons while in a vaporized state through an elongated externally heated conversion zone of restricted cross section; heating the vaporized hydrocarbons immediately following their introduction into said zone to a desired conversion temperature in excess of 1000° F. and maintaining such conversion temperature of said hydrocarbons after it has been attained substantially constant during the remaining passage of the hydrocarbons through said conversion zone by directly introducing into said hydrocarbons in regulated quantities a fluid coolant selected from the group consisting of gaseous hydrocarbons, light liquid hydrocarbons, steam, and water.

25 7. A process for the conversion of higher boiling hydrocarbons into lower boiling hydrocarbons, the steps which comprise: passing a stream of such higher boiling hydrocarbons while in a vaporized state through an elongated externally heated conversion zone of restricted cross section, heating the vaporized hydrocarbons immediately following their introduction into said zone to a desired conversion temperature, maintaining said conversion temperature substantially uniform during the remaining passage of the vaporized hydrocarbons through said conversion zone by introducing into the latter for direct admixture with said vapors a low boiling point fluid coolant selected from the group consisting of gaseous hydrocarbons, light liquid hydrocarbons, steam, and water, and regulating the volumes of the fluid coolant entering said conversion zone in a manner directly proportionate to the temperature of the vaporous hydrocarbons undergoing conversion in said zone.

30 8. In the process set forth in claim 6, the step of automatically introducing the fluid coolant into the hydrocarbons in response to the variations in temperature of the hydrocarbon vapors passing through the conversion zone.

35 9. A process for the conversion of higher boiling hydrocarbons into lower boiling hydrocarbons, the steps which comprise: passing a stream of such higher boiling hydrocarbons while in a vaporized state through an elongated externally heated conversion zone of restricted cross section; heating the vaporized hydrocarbons immediately following their introduction into said zone to a desired conversion temperature in excess of 1000° F. and maintaining such conversion temperature of said hydrocarbons after it has been attained substantially constant during the remaining passage of the hydrocarbons through said conversion zone by directly introducing water as a fluid coolant into said hydrocarbons in said conversion zone in regulated quantities, subsequently rapidly and substantially instantaneously reducing the temperature of the vapors at the end of said conversion zone to arrest abruptly conversion reactions, fractionating to produce a vapor phase cracked distillate from the converted hydrocarbons, and treating such vapor phase cracked distillate with sulphuric acid re-
